UNITED STATES PATENT OFFICE.

HAROLD F. SHEPHERD, OF GROVE CITY, PENNSYLVANIA, ASSIGNOR TO THE BESSEMER GAS ENGINE COMPANY, OF GROVE CITY, PENNSYLVANIA, A CORPORATION OF PENNSYLVANIA.

EXPLOSION ENGINE AND METHOD OF OPERATING THE SAME.

Application filed November 19, 1919. Serial No. 339,090.

To all whom it may concern:

Be it known that I, HAROLD F. SHEPHERD, a citizen of the United States, residing at Grove City, in the county of Mercer and State of Pennsylvania, have invented new and useful Improvements in Explosion Engines and Methods of Operating the Same, of which the following is a specification.

In the operation of two cycle engines difficulty is experienced in obtaining a wide range of efficient performance. If the introduction of scavenging air is such as to effect good results where the engine is running under heavy load this same introduction of air for light loads will so reduce the temperature in the combustion chamber as to make it difficult to operate. This is particularly true where the ignition is accomplished through a hot plate which receives its heat from the explosions, which heat is utilized for igniting the succeeding charges. With the scavenging charge as hereinbefore introduced for efficient running at heavy load the mean temperature of the combustion chamber when running at a very light load falls below the ignition temperature. Consequently it is impossible to maintain a hot plate at the ignition temperature from the heat of the explosion alone and if an attempt is made to continue the operation of the engine running light for any length of time the engine will stall. On the other hand if the introduction of scavenging air as heretofore introduced is controlled so as to properly take care of the light loads there is a great falling off in efficiency at the heavy loads. Heretofore the quantity of scavenging charge has been varied and the velocity of the air as it is introduced has been varied somewhat but the manner of introduction has not been such as to accomplish a correction of the difficulty above described.

I have discovered that where the scavenging air is introduced as it commonly is through a port against a deflector plate on the piston, thus directing the scavenging charge toward the opposite end of the cylinder from which it sweeps around to the exhaust port if the velocity of this scavenging charge is materially increased it mixes to a greater extent with the burnt gases of the previous explosion through the for-

nation of more pronounced eddies in the chamber and in consequence the proportionate heat of the explosions is increased as the force of the explosion is decreased, that is to say, the heat from the explosions having a lesser force is made greater if the velocity of the scavenging air as it is introduced is increased. On the other hand, when the engine is running at full load it is desirable to have the scavenging air introduced more slowly. In this instance less eddies are formed and there is a gradual displacement of the burnt gases so that there is a more complete scavenging action. Under these conditions there is enough heat developed to maintain a proper combustion in the chamber.

The results are better attained where the quantity of scavenging air is maintained approximately constant regardless of the velocity. In carrying out my invention, therefore, I vary the manner of the introduction of the scavenging air so as to increase the proportionate heat from an explosion inversely as the force of the explosion varies. In this way I am able to maintain an even running of the engine at very light loads and for any period desired and when the engine is subjected to heavy load I obtain the maximum efficiency incident to a complete scavenging by a slow introduction of scavenging air.

This method may be conveniently carried out by merely varying the clearance of the scavenging pump. By increasing the clearance the pressure of the compressed air is varied without materially changing the quantity of air that is pumped.

In the accompanying drawings I have shown a mechanism for carrying out my method and an exemplification of the mechanism forming my invention as follows:—

Fig. 1 shows a side elevation of the engine, the cylinder and immediately adjacent parts being in section.

Fig. 2 is a section on the line 2—2 in Fig. 1.

Fig. 3 a sectional view showing an alternative construction of the clearance shifting device.

1 marks the engine frame, 2 the cylinder which extends from the frame, 3 the piston in the cylinder, 4 the piston rod, and 5 the

crank shaft which is operated from the piston rod by means of a crank (not shown). The front end 6 of the cylinder operates as a pump, the piston forming a 5 plunger for the pump. The power end 7 of the cylinder has an inlet port 8 and an exhaust port 9, these ordinarily being oppositely placed in the cylinder and the piston is provided with a deflecting surface 10. 10 This operates in a well-known manner deflecting the incoming scavenging air toward the rear of the cylinder from which it sweeps around to the exhaust port 9 carrying the greater portion of the burnt gases 15 with it.

Fuel is delivered through a fuel injector 11 of any approved type and the hot plate 12 forms the bottom of a receptacle 13. A material 14, such as sulphur is provided 20 in the receptacle 13. The receptacle is closed by a condenser plate 15 which is cooled from water in the chamber 16, the chamber 16 being connected with the regular cooling system or chambers 17 of the 25 cylinder head 17a.

This hot plate is heated by the explosions and the temperature of the hot plate is kept constant at the vaporizing point of the substance retained in the receptacle by reason 30 of the fact that as soon as the substance vaporizes the vapor dissipates the heat and is condensed by the condensing surface, returning to the liquid substance after such condensation. By this means the hot plate is 35 kept at the ignition temperature which is desired. The scavenging air is drawn in through the inlet 18, passing the inlet check valve 19. A chamber 20 is arranged around the end of the cylinder and forms a receiver for the air drawn in by the piston 40 through the valve 19 and compressed as the piston moves forward. The chamber 20 is connected by a passage 21 with the inlet port 8.

45 The chamber or receiver 20 is of such size relatively to the displacement of the piston to give to the scavenging air a pressure which when delivered through the inlet port as this port is uncovered by the piston is 50 higher than is desirable for the highest economy, that is to say, the velocity is so great that eddies are formed in the cylinder and more or less of the incoming air is mixed with the burnt gases so that a 55 higher temperature is maintained with this high velocity than is desirable where the engine is running under heavy load but gives a mean temperature which is sufficient to maintain the hot plate at ignition 60 temperature. Consequently the engine can idle with the delivery of air so arranged.

In order to provide for greater economy that will arise from a slower introduction of air when the engine is working heavily 65 I provide a supplemental chamber which in-

creases the clearance between the piston and the inlet port and consequently reduces the pressure at which air is introduced. A plate 22 is secured to the side of the chamber 20 and a clearance controlling device 23 is secured to this plate. A passage 24 extends from the chamber 20 through the plate 22 and into the body of the device 23. This passage extends through a valved opening 25 and by way of a passage 26 and opening 27 to a supplemental chamber 28 arranged below the chamber 20. A valve 29 controls the opening 25. It is provided with a stem 30 which extends upwardly and is secured to a piston 31. The piston 31 70 operates in a cylinder 32. A small passage 33 connects the passage 24 with the upper end of the cylinder 32. A valve 34 controls the passage 33. The valve 34 is provided with a stem 35 and a spring 36 maintains 75 the valve normally in closed position. The stem is provided with a button 37 at its upper end in position to be engaged by an arm of a rock lever 38. The rock lever is pivoted at 39 on an arm 40 extending from the body of the device 23. A link 41 connects the rock lever 38 with a rock lever 42. The rock lever is pivoted at 42a on an arm 42b extending from the 80 governor frame 50. One arm of the rock lever is connected to a sliding spool 43 connected by links 44 with the governor weights 45. The weights 45 are carried by links 46 from a cross head 47. The cross head 47 is mounted on a shaft 48. The shaft 48 is journaled in the bearing 49 and stepped on the bearing by means of a collar 51. A bevelled gear 52 is fixed on the shaft 48 and engages a bevelled gear 53. The bevelled gear 53 is fixed on a shaft 54, the 85 shaft 54 being mounted in bearings 55. A pulley 56 is mounted on the shaft 54. A belt 57 extends from the pulley 56 to the pulley 58 on the engine shaft. It will be 90 readily seen that as the engine speeds up and the governor weights are carried outwardly the rock arm 38 through the linkage shown and described is rocked so as to open the valve 34 thus opening communication 95 between the upper end of the cylinder by way of the passage 33 with the passage 24, under which circumstances the pressure both sides of the piston 31 is balanced. The valve 29 under these circumstances is closed by a spring 29a and the scavenging air then 100 is confined to the chamber 20 and enters the cylinder with a velocity which has heretofore been described. It will be understood that for a few strokes of the engine air 105 will be delivered past the valve 29, the valve 29 acting as a check until the chamber 28 is 110 filled to the higher pressure.

When, however, the engine slows down under load the governor balls drop and this movement is communicated through the 115 120 125 130

linkage described so as to move the rock arm 38 out of engagement with the button 37, thus permitting the closing of the valve 34. Under these circumstances the valve 34 acts as a check and air is pumped into the cylinder 32 until the pressure above the piston reaches the maximum pressure. At the same time the pressure under the valve 29 is the maximum pressure and consequently the area of the valve 29 should be less than the piston 31 so that when the pressure in the chamber 20 or on the underside of the piston 31 is at its lowest the preponderance of pressure above the piston is sufficient to overcome the pressure below the valve 29 supplemented by the spring 29^a and thus open the valve 29. The air above the piston remains trapped by the valve 34 and any leakage, of course, is taken care of with each pulsation of the pump so that the valve 29 is maintained in its open position. This opening of the valve takes place in a very few strokes. During the time the valve 29 is open the clearance space includes not only the chamber 20 but the chamber 28 as before described.

It will be noted, however, that notwithstanding this greater clearance and smaller compression the amount of scavenging air which is introduced will remain approximately constant and consequently there will be as large a volume under the conditions of less velocity as with the higher velocity. There will be, therefore, a better scavenging and a more efficient operation of the engine under heavy load because with a slow introduction of air the incoming air does not so intimately intermingle with the burnt gases and therefore there is a lower mean temperature in the explosion chamber than would be the case if the scavenging were less perfect.

In Fig. 3 there is shown an alternative construction of a clearance controlling device in which a manually controlled valve 59 is substituted for the valve 29. The valve 59 is a rotary valve and has a way 60 which can be brought into register with the way or passage 24 giving an easy bend into the passage 26. The valve is supplied with a pulley 61 to which may be attached a cord by means of which the valve may be operated from a distance.

What I claim as new is:—

1. In an explosion engine, the combination of a combustion chamber; means for introducing and igniting fuel to effect a two cycle operation; means for introducing equal quantities of scavenging air with each explosion; and means for varying the velocity of the air as it is introduced inversely as the force of the explosion varies.

2. In an explosion engine, the combination of a combustion chamber; means for introducing and igniting fuel to effect a two cycle operation; a pump synchronized with said engine compressing scavenging air;

means for conveying the air compressed to the combustion chamber; and means for varying the clearance of the pump to vary the pressure of the air compressed and its velocity on its introduction to the combustion chamber, said clearance being increased as the force of the explosion is increased. 70

3. In an explosion engine, the combination of a combustion chamber; a piston operating in the chamber; means for introducing and igniting fuel to effect a two cycle operation; a pump in which the piston acts as the displacing element; means for conveying air from the air pump to the combustion chamber; and means for increasing the clearance of the pump as the force of the explosion increases. 75 80

4. In an explosion engine, the combination of a combustion chamber; means for introducing and igniting fuel to effect a two cycle operation; a pump synchronized with said engine compressing scavenging air; means for conveying the air compressed to the combustion chamber; and automatic means for varying the clearance of the pump to vary the pressure of the air compressed and its velocity on its introduction to the combustion chamber, said clearance being increased as the force of the explosion is increased. 90

5. In an explosion engine, the combination of a combustion chamber; a piston operating in the chamber; means for introducing and igniting fuel to effect a two cycle operation; a pump in which the piston acts as the displacing element; means for conveying air from the air pump to the combustion chamber; and automatic means for increasing the clearance of the pump as the force of the explosion increases. 95 100

6. In an explosion engine, the combination of a combustion chamber; a hot plate subjected to the heat of the explosions for igniting the charges in said chamber; means for introducing equal quantities of scavenging air with each explosion; and means for varying the velocity of the air as it is introduced inversely as the force of the explosion varies. 105 110

7. In an explosion engine, the combination of a combustion chamber; a hot plate subjected to the heat of the explosions for igniting the charges in said chamber; means for maintaining said hot plate at a constant temperature; means for introducing equal quantities of scavenging air with each explosion; and means for varying the manner of introduction of the air to vary the proportionate heat retained from an explosion inversely as the force of the explosion varies. 115 120 125

8. In an explosion engine, the combination of a combustion chamber; a hot plate subjected to the heat of the explosions for igniting the charges in said chamber; means for maintaining said hot plate at a constant 130

temperature; means for introducing equal quantities of scavenging air with each explosion; and means for varying the velocity of the air as it is introduced inversely as the force of the explosion varies.

9. In an explosion engine, the combination of a combustion chamber; means for introducing and igniting fuel to effect a two cycle operation; a pump synchronized with 10 said engine compressing scavenging air; an auxiliary clearance chamber for said pump; means for conveying the air from the pump to the combustion chamber; and automatic means for connecting and disconnecting the 15 auxiliary clearance chamber from the pump, said means connecting the auxiliary clearance chamber with the pump as the force of the explosion decreases.

10. In an explosion engine, the combination of a combustion chamber; a hot plate 20 subjected to the heat of the explosions for igniting the charges in said chamber; a pump synchronized with said engine compressing a scavenging air; an auxiliary 25 clearance chamber for said pump; means for conveying the air from the pump to the combustion chamber; and automatic means for connecting and disconnecting the auxiliary clearance chamber from the pump, said 30 means connecting the auxiliary clearance chamber with the pump as the force of the explosion increases.

11. In an explosion engine, the combination of a combustion chamber; a hot plate 35 subjected to the heat of the explosions for igniting the charges in said chamber; means for maintaining said hot plate at a constant temperature; a pump synchronized with said engine compressing a scavenging air; an auxiliary clearance chamber for said 40 pump; means for conveying the air from the pump to the combustion chamber; and automatic means for connecting and disconnecting the auxiliary clearance chamber from the pump, said means connecting the auxiliary clearance chamber with the pump as the force of the explosion increases.

12. The method of operating two cycle 50 explosive engines which consists in exploding a mixture; introducing a scavenging air; varying the manner of introducing the air and varying its admixture with the burnt gases and thus varying the proportionate heat retained from the explosion 55 inversely as the force of the explosion varies; and introducing a fuel to form an explosive mixture.

13. The method of operating two cycle 60 explosive engines which consists in exploding a mixture; introducing a scavenging air; varying the manner of introducing the air and varying its admixture with the burnt gases and thus varying the proportionate heat retained from the explosion 65 inversely as the force of the explosion varies;

introducing a fuel to form an explosive mixture; and varying the fuel introduced to vary the force of the explosion.

14. The method of operating two cycle 70 explosive engines which consists in exploding a mixture; introducing equal quantities of scavenging air; varying the manner of introducing such air to vary its admixture with the burnt gases to vary the proportionate heat retained from an explosion 75 inversely as the force of the explosion varies; and introducing a fuel to form an explosive mixture.

15. The method of operating two cycle 80 explosive engines which consists in exploding a mixture; introducing a scavenging air; directing the air and varying its velocity to vary its admixture with the burnt gases to vary the proportionate heat retained from an explosion 85 inversely as the force of the explosion varies; and introducing fuel to form an explosive mixture.

16. The method of operating two cycle 90 explosive engines which consists in exploding a mixture; introducing equal quantities of scavenging air; varying the velocity of the air as introduced inversely as the force 95 of the explosion varies; and introducing fuel to form an explosive mixture.

17. The method of operating two cycle 100 explosive engines which consists in exploding a mixture by igniting the mixture from heat generated in preceding explosions; introducing a scavenging air; varying the manner of introducing the air and varying its admixture with the burnt gases and thus varying the proportionate heat retained from the explosion 105 inversely as the force of the explosion varies; and introducing a fuel to form an explosive mixture.

18. The method of operating two cycle 110 explosive engines which consists in exploding a mixture by igniting the mixture from heat generated in preceding explosions; introducing equal quantities of scavenging air; 115 varying the manner of introducing such air to vary its admixture with the burnt gases to vary the proportionate heat retained from an explosion inversely as the force of the explosion varies; and introducing a fuel to form an explosive mixture.

19. The method of operating two cycle 120 explosive engines which consists in exploding a mixture by igniting the mixture from heat generated in preceding explosions; introducing a scavenging air; varying the velocity 125 of the air as introduced inversely as the force of the explosion varies; and varying its admixture with the burnt gases and thus varying the proportionate heat retained from an explosion and introducing fuel to form an explosive mixture.

20. The method of operating two cycle 130 explosive engines which consists in exploding a mixture by igniting the mixture from heat

generated in preceding explosions; introducing equal quantities of scavenging air; varying the velocity of the air as introduced inversely as the force of the explosion varies; and introducing fuel to form an explosive mixture.

21. The method of operating two cycle explosive engines which consists in exploding a mixture; compressing scavenging air with 10 impulses corresponding to the explosions and introducing said scavenging air with each compression to a point of explosion; varying the manner of introducing the air and varying its admixture with the burnt 15 gases and thus varying the proportionate heat retained from the explosion inversely as the force of the explosion varies; and introducing a fuel to form an explosive mixture.

22. The method of operating two cycle explosive engines which consists in exploding a mixture; compressing scavenging air with impulses corresponding to the explosions and introducing said scavenging air with 25 each compression to a point of explosion; varying the velocity of the air as introduced inversely as the force of the explosion varies; and varying its admixture with the burnt gases and thus varying the proportionate heat retained from an explosion and 30 introducing fuel to form an explosive mixture.

23. The method of operating two cycle ex-

plosive engines which consists in exploding a mixture; compressing scavenging air with 35 a constant displacement and introducing the same; varying the manner of introducing the air to vary its admixture with the burnt gases to vary the proportionate heat retained from the explosion inversely as the 40 force of the explosion varies; and introducing a fuel to form an explosive mixture.

24. The method of operating two cycle explosive engines which consists in exploding a mixture; compressing scavenging air 45 with a constant displacement and introducing the same; varying the velocity of the air as introduced inversely as the force of the explosion varies; and introducing fuel to form an explosive mixture.

25. The method of operating two cycle explosive engines which consists in exploding a mixture; compressing scavenging air with impulses corresponding to the explosions and with a constant displacement and introducing the same; varying the manner of introducing the air to vary its admixture with the burnt gases to vary the proportionate heat retained from the explosions inversely as the force of the explosions vary; 55 and introducing a fuel to form an explosive mixture.

In testimony whereof I have hereunto set my hand.

HAROLD F. SHEPHERD.
